UNITED STATES PATENT OFFICE.

GEORGE W. NAYLOR, OF CATSKILL, NEW YORK.

COLLAPSIBLE LADDER.

SPECIFICATION forming part of Letters Patent No. 740,460, dated October 6, 1903.

Application filed September 26, 1902. Serial No. 124,980. (No model.)

To all whom it may concern:

Be it known that I, GEORGE W. NAYLOR, a citizen of the United States, residing in Catskill, Greene county, and State of New York, have invented a novel Collapsible Ladder, of which the following is a specification.

The subject of the present invention is a ladder which while more particularly designed for embodiment as a step-ladder for service in connection with marine and sleeping-car berths is also applicable to ladders intended for other purposes.

An important feature of the invention resides in the fact that the novel character and relation of the means connecting the steps with the ladder sides are such that while they securely support said steps and sides when the ladder is adjusted for use and tend to draw said sides toward each other, and therefore contribute to mutually brace said steps and sides as weight is imposed on any of the former, said connections readily admit of the collapsing of the ladder for causing it to assume a compact condition without involving the disengagement of the connecting means with either the steps or sides.

There are other novel features connected with the invention which, in addition to those above alluded to, are described at length in the subsequent detailed description.

In the accompanying drawings, forming part of this specification, Figure 1 is a perspective view representing a portion of a marine state-room and illustrating my novel step-ladder adjusted for service. Fig. 2 is an elevational view showing, on a larger scale, the ladder in its collapsed condition and illustrating the same as being conveniently suspended from the side of the berth-frame. Fig. 3 is a detail view showing, also on an enlarged scale, the position occupied by one of the steps and its suspending links with reference to the ladder sides when in the open position. Fig. 4 is an enlarged sectional detail view illustrating certain features and adaptations of the upper engaging hooks.

Similar reference characters designate corresponding parts throughout the several figures of the drawings where they occur.

The parallel side members A A of the ladder, or, as they will generally hereinafter be

referred to as the "ladder sides," are of suitable length, that deemed most desirable enabling them to extend from a point contiguous to the top edge of the side frame D of the upper berth to a point terminating a short distance above the floor. With a view to securing lightness these ladder sides will be as thin as possible commensurate with the strength required, and with the idea of further lightening the weight of the construction the sides A A have extended openings a located intermediately between the upper and lower ends and the planes of the contiguous upper and lower steps B B and between those of the latter and that of the middle step B. While I have shown the ladder as having three steps, as is generally customary, it is manifest that the number may vary according to requirement.

In the outer face of each side A, in planes slightly above those occupied by the steps B when in position, are shallow horizontal recesses which are guarded by thin metallic plates a', preferably let into the material of the side so as to be flush therewith and rigidly secured in any suitable manner. These plates serve as keepers for retaining within the recesses the outer horizontal portions b of angular links B', but permit their free pivotal movement within said recesses. The links have, further, inner horizontal portions b', extending similar to the portions b and pivotally engaging recesses therefor in the under side of the adjacent part of the contiguous step B. Shallow plates b'', flush in the under faces of the steps, perform an office for the portions b' similar to that which the plates a' perform for the portions b. The ends B'' of the steps are outwardly beveled and are adapted, when the ladder is arranged for use, to bear in correspondingly-shaped notches b''' therefor in the inner faces of the sides A.

Pivotedly mounted on the inner face of each side A, near the upper end thereof, is a metal suspending device C of peculiar configuration and function, each device consisting of an extended shank c, straight on its inner face and merging into the hook c', the seat c'' of which is approximately at a right angle with respect to the inner face of its shank

and the inner face of its nose c^3 . These devices are preferably ribbed or filleted for augmenting the strength thereof.

The operation and advantages of the novel ladder will be readily understood. With the parts arranged as disclosed in Fig. 1 a light and conveniently-handled step-ladder is presented, wherein the steps are firmly and positively retained in position to sustain any reasonable weight which may be imposed. This results not only from the fact of their beveled ends bearing in the notches b^3 , but also by reason of the opposite oblique disposition of the links B' , the peculiar arrangement of which will operate to more firmly draw the sides A together, and thus more positively retain the bevel ends in the notches as the weight on the steps increases.

The adjustment of the ladder in position is accomplished by causing the hooks of the devices C to take over the upper edge of the side frame D of the upper berth. In instances where no guard-rail D' is located on the inner side of said rail the shanks c are swung outward on their pivots, so that while the seating c^2 bears intimately on the top edge of the frame D the inner side of the nose c^3 will engage positively against the inner side of the frame. Palpably where the guard-rail D' is present a corresponding engagement can be made by simply swinging the devices C inward to a slight extent. Under either circumstances the engagement will permit the ladder to depend in contact with the side frames of the upper and lower berths in a manner that will tend to avoid liability of the devices C becoming undesirably disengaged. Furthermore, such safe engagement will be maintained under any swaying of the ladder incurred through the motion of the vessel or car.

When the ladder is not required for service, one of the devices C is disengaged from the frame D , and the weight of the side A , coupled with the presence of the link connections, will permit the construction to collapse in a compact manner, with the steps folded against the suspended side A and the detached side against both, as indicated in Fig. 2. As thus arranged the ladder in its highly-reduced form can be stowed to one side without occupying any appreciable amount of room. In fact, in its collapsed form its bulk is so inconsiderable that it can be suspended from the upper frame D at the foot of the berth and not be in the way.

The peculiar supporting provision for the steps readily permits the collapsing operation notwithstanding the capacity for firmly retaining said steps when the ladder is in its adjusted position, as it stoutly resists all downward force exerted on the steps, but readily yields to power exerted in the opposite direction.

From the foregoing description it will be appreciated that the novel ladder is not only

highly serviceable, but is simple and comparatively inexpensive in construction.

Having now described my invention, what I claim as new, and desire to secure by Letters Patent, is—

1. The combination in a ladder comprising side members and steps, of step-supporting links having outer and inner horizontal portions movably but permanently engaged with the side members and steps respectively within the planes presented by the outer faces of the former and bottom surfaces of the latter, whereby the material of the members and steps bears the strain incurred by said links, which in turn permit the steps to fold parallel with one of the side members and the other member to assume a corresponding position with respect thereto.

2. The combination in a ladder comprising side members having horizontal recesses at their outer sides, and steps with under horizontal recesses, of step-supporting links provided with outer horizontal portions bearing in the side recesses and inner horizontal portions within the step-recesses, plates a', b' , secured to said members and steps and pivotally confining the link portions therein, said links permitting the steps to fold parallel with one of the side members and the other member to assume a corresponding position with respect thereto.

3. A ladder comprising side members, steps, and inwardly - converged depending links movably but permanently connecting the steps and side members, said links tending to move said members toward each other, as downward pressure is exerted on any of the steps and also adapted to permit the steps to fold parallel with one of the side members and the other member to assume a corresponding position with respect thereto; and suspending means located at the upper portion of the ladder.

4. A ladder comprising side members, steps, and inwardly - converged depending links movably but permanently connecting the steps and side members, said links tending to move said members toward each other, as downward pressure is exerted on any of the steps and also adapted to permit the steps to fold parallel with one of the side members and the other member to assume a corresponding position with respect thereto; and relatively independent suspending devices located on the ladder.

5. A ladder comprising side members with inner notches, steps, and means attaching the steps to the side members, said means tending to move said side members toward each other and thereby more intimately seat the step ends in the notches and also adapted to permit the steps to fold parallel with one of the side members and the other member to assume a corresponding position with respect thereto.

6. A ladder comprising side members with inner notches, steps, and links movably but

permanently connecting the steps to the side members, said links tending to move said side members toward each other and thereby more intimately seat the step ends in the notches and also adapted to permit the steps to fold parallel with one of the side members and the other member to assume a corresponding position with respect thereto.

7. A ladder comprising side members with inner angular notches as indicated, steps both ends of which are provided with upper outwardly-inclined bevels to conform said ends with the notches, and means attaching the steps to the side members, said means tending to move the latter toward each other and thereby more intimately seat the bevel ends of the steps in the notches and also adapted to permit the steps to fold parallel with one of the side members and the other member to assume a corresponding position with respect thereto.

ends of which are provided with upper outwardly-inclined bevels to conform said ends with the notches, and means attaching the steps to the side members, said means tending to move the latter toward each other and thereby more intimately seat the bevel ends of the steps in the notches and also adapted to permit the steps to fold parallel with one of the side members and the other member to assume a corresponding position with respect thereto.

In testimony whereof I have signed my name to this specification in the presence of two subscribing witnesses.

GEORGE W. NAYLOR.
